UNITED STATES PATENT OFFICE.

JOHN A. JONES, OF CINCINNATI, OHIO.

TILE.

968,162.

Specification of Letters Patent. Patented Aug. 23, 1910.

Application filed July 17, 1908. Serial No. 444,010.

To all whom it may concern:

Be it known that I, JOHN A. JONES, a citizen of the United States of America, and resident of Cincinnati, county of Hamilton, 5 State of Ohio, have invented certain new and useful Improvements in Tiles, of which the following is a specification.

My invention relates to a tile covering for walls, floors, etc. Its object is such a covering, in which each tile is held to the wall or floor firmly along each side by nails, which are hidden from view, and of which a minimum number are required to attain the result and in which an efficient key-seat is 15 formed between the tiles for concrete.

Referring to the accompanying drawings, Figure 1 is a perspective view of a tile embodying my invention. Fig. 2 is an elevation of a tile construction embodying my invention. Fig. 3 is a sectional view taken upon line $x-x$ of Fig. 2, but upon an enlarged scale. Figs. 4 and 5 are views of modifications, the views being similar to Figs. 1 and 2.

Referring to Figs. 1, 2, and 3, each tile consists of parallel rectangular plates, A, A', and an intervening strip, a, all of which are formed integral. Plate, A, is placed so that its opposite edges, a' , a^2 , are staggered with 25 the edges, a^3 , a^4 , of the plate, A', and so that its ends, a^5 , a^6 , are staggered with the ends, a^7 , a^8 , of the plate, A'. The intervening strip, a, is of dimensions such that groove, a^9 , surrounds the tile. In securing these tiles to 30 the wall, B, a row of nails, c, may be driven into the wall so as to leave their heads projecting out beyond the wall a distance equal to the thickness of the plate, A'. Then the first row of tile are placed so that the heads 35 of the nails, c, take into the groove, a^9 , and the edge, a' , of the plate, A, overlaps the nails. Then nails, c', are driven into the 40 walls, so that their heads engage the edge, a^4 , of the tile. There are preferably two nails 45 used upon the edge of each tile and are placed upon each side of the center of the

tile. After the rows of nails, c', have been secured in place, the second row of tiles are placed with their edges, a' , projecting over the nails, c', and over the edge, a^4 , of the 50 first row of tiles. The nails, c', hold the adjacent edges of the tiles firmly to the wall, B, and likewise serve to properly space the tiles apart. The projecting ends, a^5 , of one tile overlaps the end, a^8 , of its adjacent tile. 55 After the tiles have been thus secured in place, the concrete, D, is grouted into the grooves between adjacent rows of tiles.

In the modification shown in Figs. 4 and 5, while the sides of the plates, A², are staggered with the sides of the plate, A³, in a manner similar to the sides of the plates, A, and A', the ends, a^{10} , a^{11} , of the plate, A², are in the same plane with the ends, a^{12} , a^{13} , of the plates, A³. The manner of securing 60 the tiles made up of the plates, A², A³, in place is similar to that shown in Figs. 1 and 2, except that instead of having the ends of the tiles overlap each other, they are held in place by the heads of nails, c². 70

In both modifications, a base plate, E, may be used to cover the lower edges of the first row of tiles.

What I claim is:

A tile covering for a wall consisting of a 75 series of tiles, each tile having a flange projecting from the upper half of one of its sides and a groove formed between the flange and the lower half of the corresponding side, and a second flange projecting from 80 the lower half of the opposite side of the tile, the tiles being placed side by side with the first named flanges projecting over the second flanges, and a series of nails for holding 85 the tiles to the wall, the head of each nail holding the abutting edges of two tiles to the wall.

JOHN A. JONES.
